UNITED STATES PATENT OFFICE.

THOS. B. RAYMOND, OF SAGINAW, MICHIGAN.

IMPROVED RAFTING-PIN.

Specification forming part of Letters Patent No. **59,072**, dated October 23, 1866.

To all whom it may concern:

Be it known that I, THOMAS B. RAYMOND, of Saginaw, in the county of Saginaw and State of Michigan, have invented a new and useful Improvement in Rafting-Pins; and I do hereby declare that the following is a full, clear, and exact description thereof, which will enable others skilled in the art to make and use the same, reference being had to the accompanying drawings, forming part of this specification, in which—

Figure 1 is a vertical cross-section of one of the logs through the center of one of my improved pins, and showing the rope in place. Fig. 2 is a vertical longitudinal section through one of the logs at the side of one of my improved pins. Fig. 3 is a top view of a portion of a raft, my improved pin being used in four logs, and the ordinary pin in three. Fig. 4 is an end view of the portion of a raft represented in Fig. 3.

Similar letters of reference indicate like parts.

In sections of the country where rafting is carried on an immense expenditure of time and money is annually incurred in making rafting-pins and in cleaning the rope after the raft has been broken up upon reaching its destination. It is estimated that upon the Saginaw river alone about three and a half millions of pins are made and used annually at an expense of about fifteen thousand dollars, including the expense of cleaning the rope.

The object of my invention is to diminish these expenses, and at the same time to furnish a better pin; and consists of a wedge-shaped pin so formed as to hold a straight rope, thereby removing any necessity for cleaning the rope.

A B are the logs forming the raft. The logs A are represented as being secured together

in the ordinary way—that is, by driving into the logs round, square, or octagonal pins C, the rope D extending from pin to pin, and being knotted around each, as represented, about half the rope being employed in forming the knots around the pins.

My improved pin E is made in the form of a wedge, as shown in Figs. 1 and 2, with a notch or channel, F, extending from the edge of the pin or wedge far enough toward its head to allow the wedge to be driven firmly into the log and still leave enough of said notch F above the log to allow the rope D to pass through it, as represented in the drawings. The bottom of the notch F is made curved, so as to fit around the rope and hold it firmly to the log.

In using these pins or wedges E the rope is extended from log to log, the wedge placed over the rope and driven into the log, so as to hold the rope between the surface of the log and the bottom of the channel F, as represented in the drawings.

By this improvement only about one-half as much rope is required as is necessary when the old method is employed. The rope does not require to be cleaned, since it frees itself at once from the pins, and there are no kinks or knots to be removed; and the pins may be made by machinery, thus materially lessening the cost of manufacturing them.

I claim as new and desire to secure by Letters Patent—

A rafting-pin made in wedge form, and having a notch or channel extending up from its point or edge, for receiving and grasping a straight rope, substantially as described, and for the purpose set forth.

THOMAS B. RAYMOND.
